ABSTRACT: A form feeding attachment for use with addressing machines or the like includes friction rollers for feeding a form from a supply stack to a preprint station, and a conveyor tape for advancing the form from the preprint station to a printing station of the machine where it is held by an automatically operated stop, and then to a receiving hopper. The friction rollers and the conveyor tape are intermittently driven in timed relation with the printing machine such that while a form is being imprinted at the printing station the conveyor tape is inactive and the friction rollers are driven to feed the next form in the stack to the preprint station. On completion of the printing operation, the friction rollers are inactivated and the conveyor tape is driven to advance the form from the printing station to the receiving hopper and the form at the preprint station to the printing station. Means are also provided for detecting the presence or absence of a form at the preprint station and, if the conditions of form presence or absence are not satisfied, the machine is shut down without loss of a printing operation at the printing station. Self-regulating means are provided to adjust the timing of the form stopping and detecting means to accommodate slight differences in the machines to which the attachment is applied. The form stop at the printing station can be adjustably positioned without affecting its drive or timing.

WORKPIECE FEEDING ATTACHMENT FOR A TRAVELING CYLINDER ADDRESSING MACHINE

BACKGROUND OF THE INVENTION

The present invention relates to a form feeding device and, more specifically, to a form feeding attachment for feeding envelopes, postal cards and the like to a printing station of an addressing machine. Conventionally, addressing machines are adapted to imprint forms and documents from embossed printing plates by placing a form over an inked ribbon which overlies the printing plate, and causing a platen to apply printing pressure thereagainst to produce an imprint on the form.

Small volume printing applications generally resort to the use of hand operated addressing machines in which it is necessary to manually position a form to be imprinted at the printing station. Normally, such machines are provided with guides or stops against which the form is registered when it is placed in printing position and, after the imprinting operation is completed, the form is manually removed and replaced with a new form. While this method of addressing cards and envelopes provides legible and accurate impressions, it does not provide for high-speed operation and, therefore, as mentioned above, is limited to low volume printing applications.

Still other addressing machines are electrically operated and are arranged with form feeding attachments for automatically feeding forms to the printing station of the machine. Depending on the nature of the material to be imprinted, various feeders are available such as suction, friction, shuttle, needle feeders, etc. A feeding attachment of this kind is primarily used for bulk mailing applications wherein the material being imprinted is in the nature of booklets, pamphlets, brochures and the like and, wherein the volume of the work is great enough to justify the additional cost of such a feeding attachment.

While these feeders are reliable in operation and greatly increase the operating speed, as compared to manual addressing applications, they do not lend themselves particularly to moderate size applications and especially to those applications in which small size forms such as envelopes and postal cards are being fed and imprinted.

It is an object of the present invention to provide a compact form feeder adapted to be readily installed as an attachment on existing addressing machines.

Another object is to provide a form feeding attachment for advancing a form from a supply stack to a preprint station while a preceding form is being imprinted, and for feeding the form from the preprint station to the printing station while the preceding imprinted form is conveyed to the collection hopper.

Another object is to provide a form feeding device which includes sensing means for detecting the presence or absence of a form at the preprint station, and to control machine shutdown if a form is not present at the preprint station.

Another object of the invention is to provide a feeder which operates to advance a form to the preprint station simultaneously with the imprinting of a preceding form at the printing station, and to advance the form at the preprint station to the printing station simultaneously with the conveyance of the imprinted form from the printing station to the receiving hopper.

Another object is to provide a feeding device adapted to feed forms in a straight path from the front to the rear of an addressing machine in timed relation with the feeding of a printing device from a supply magazine to the printing station of the machine.

Still another object is to provide a form feeder which is reliable in operation, and operable to feed the forms at a fairly high rate of speed, and nevertheless relatively inexpensive to produce.

Other objects, features and advantages will appear hereinafter as the description proceeds.

IN THE DRAWINGS

FIG. 1 is a top plan view of a form feeding device in accordance with the practice of the present invention with the top of the printing machine shown in phantom lines;

FIG. 2 is a side elevation of the form feeding device of FIG. 1 mounted on a printing machine with only a fragmentary view in phantom of the printing machine top and platen mechanism being shown;

FIG. 3 is a top plan view in detail of the form feeding device, the view being broken to accommodate it to the page;

FIG. 4 is a section taken substantially on line 4-4 of FIG. 3;

FIG. 5 is a detail plan of the mechanism for actuating and positioning a form stop member drawn to a larger scale;

FIG. 6 is a schematic wiring diagram of a form detection circuit and includes a diagrammatic showing of the main drive shaft and cams associated therewith, as they would appear looking from the left-hand side in FIG. 3; and

FIG. 7 is a detail perspective on a reduced scale showing the connection of a cable drive means from the printing machine to the form feeding device.

DESCRIPTION OF THE PREFERRED EMBODIMENT

The feeder device of the present invention is adapted to be used, for example, with a printing machine as disclosed in U.S. Pat. No. 2,359,850. In such a machine, embossed printing plates are passed sequentially and in a step-by-step manner from a supply magazine to a printing station and then to a receiving drawer.

A roller platen is provided at the printing station and is operated each machine cycle to produce an impression from a printing plate, through an inked ribbon and onto a form or sheet. During the forward stroke (i. e., the nonprinting stroke) the platen is spaced from the form to be imprinted and a form and a printing plate are advanced to the printing station, and during the rearward stroke (i. e., the printing stroke) the platen is lowered into pressure engagement with the form overlying the printing plate to image the form. On completion of an imprinting operation the platen is again raised to a position spaced from the form.

As shown in FIGS. 1 and 2, the feeding device is positioned on the table top of a printing machine 2, and is secured at the front edge of the table top by a clamping means 4. The feeding device extends from the front to the rear of the machine and passes under a printing head 6 which carries a platen roller P and a drive lever 8 as best shown in FIG. 2. The lever 8 has a predetermined back and forth oscillating motion which could, of course, also be back and forth translation so far as the present invention is concerned, and for the sake of this disclosure the term "reciprocating" will be employed to cover this type of motion generally.

The feeding device comprises a supply hopper 10 for retaining on edge a stack of forms F to be imprinted, a feed roller mechanism indicated generally at 12 for advancing a form from the stack to a preprint station indicated at 14, a conveyor mechanism 16 for advancing a form from the preprint station to a work station or printing station indicated at PS and from there to a deflector 17 which guides the form into a receiving hopper 18 mounted at the rear of the machine.

As shown in FIGS. 1, 2, 3 and 4, the supply hopper 10 is mounted between a pair of side plates 20 and 22, and includes a deck plate 24 inclined downwardly towards the feed roller mechanism 12 for supporting the workpieces or forms F. A separator blade 26 is mounted on the top face of the deck plate 24 and is movable towards and away from a series of separator rollers 28. The setting of the separator blade in relation to the separator rollers is determined by the thickness of

the forms being fed, such that the gap or exit between the front edge of the blade and the separator rollers permits the passage therethrough of only a single form at a time. When the blade 26 is properly set it is locked in place by a thumb screw 30. A form follower 32 for supporting the rear of the stack of forms is positioned on the separator blade and is adapted to

move by gravity against the stack, and to be manually moved away from the stack when forms are being placed in the hopper. The follower 32 is guided in its movement by grooved rollers 34, mounted on the underside of the follower, which are in rolling engagement with the edges of the separator blade 26.

The supply hopper 10 is further provided with a pair of side guides 36 and 38 for positioning and guiding the forms in the hopper. The side guides are slidably mounted on a rod 40 fixed in the side plates 20 and 22, and are locked in position on the rod by thumb screws. Additionally, form guides 42 and 44 are slidably mounted on the rod 40 and act against the top edge of the stack of forms F to maintain the forms in an upright position against follower the follower 32. The form guides are also held in place on the rod by thumb screws.

The feed roller mechanism 12 comprises the separator rollers 28 mounted on a shaft 48 rotatably journaled in the side plates 20 and 22 as best shown in FIG. 3. The separator rollers are preferably made of rubber and are provided with knurled peripheries to provide a positive gripping action against the first form in the stack to separate it from the rest of the stack and advance it to the preprint station 14. The shaft 48 is driven by a chain 50 which is trained about a sprocket 52 provided on the shaft 48 and a sprocket 54 provided on a main drive shaft 56. Also, the shaft 48 is provided with a knob 58 to permit manual rotation of the separator rollers 28 as will be further explained below.

An overload relief device 60 is associated with the separator rollers 28 and provides a safety feature to prevent damage to the feed mechanism. In particular, if more than one form at a time tries to become separated from the stack, thereby causing a jam, the added thickness of the multiple forms will tend to hold the separator rollers 28 against rotation and the overload relief device allows the shaft 48 to continue to rotate.

The feed roller mechanism 12 also includes a pair of pullout rollers 62 and 64 mounted on a shaft 66 rotatably supported in the side plates 20 and 22. One end of the shaft 66 is provided with a gear 68 in mesh with a gear 70 on the main drive shaft 56 for driving the shaft 66 and the pullout rollers mounted thereon. A pressure roller 72 is positioned beneath each pullout roller (only one being shown in FIGS. 3 and 4) and projects through an opening in the deck plate 24 and into engagement with the pullout rollers. The pressure rollers are supported in brackets 76 (only one being shown in FIGS. 3 and 4) and the brackets are pivotally mounted on a rod 80 fixed in the side plates 20 and 22. The pressure rollers are maintained in engagement with the pullout rollers by springs 82 (only one being shown in FIGS. 3 and 4) which urge the brackets in a clockwise direction as viewed in FIG. 4. These pressure rollers coacting with the pullout rollers are effective to feed a form F out of the preprint station 14 when the shaft 66 is driven as will be further explained below.

The conveyor mechanism 16 comprises a housing providing a sidewall 89 and the side plate 22, an endless conveyor tape 90 for transporting a form from the preprint station to the printing station and, subsequently, to the receiving hopper 18, as shown in FIGS. 1, 2 and 3. The conveyor tape passes around a tape drive drum 92 mounted on a shaft 94 supported in the side plates 20 and 22. The shaft 94 is driven by a chain 96 which is entrained about a sprocket 98 provided on the main drive shaft 56 and a sprocket 100 provided on the shaft 94. From the tape drive drum 92 the lower reach of the conveyor tape extends across the table top of the printing machine 2 and around a roller 102, and the top reach of the conveyor tape passes over a roller 104, under a series of guide rollers 106 and, as shown in FIGS. 3 and 4, under an idler roller 108 adjacent the tape drive drum. As will be further described hereinafter, a form being transported is carried at one end by the top reach of the conveyor tape and it is held thereagainst by the series of rollers 106. The series of guide rollers 106 are carried by a mounting bracket 110 secured to the sidewall 89, and each of the rollers is spring loaded to urge the rollers into engagement with the conveyor tape.

Preferably, the bracket supporting the rollers 102 and 104 is made adjustable so as to permit obtaining proper tension adjustment of the conveyor tape 90.

From the description thus far, it will be seen that the feed rollers 62 and 64, the separator rollers 28, and the conveyor tape 90 are all driven directly from the main drive shaft 56. The arrangement for driving the main drive shaft will now be described with reference to FIGS. 2, 3 and 7. A drive cable 112 is connected at one end to the reciprocating drive lever 8 and extends rearwardly around a pulley 114. The other end of the drive cable is connected to one end of a chain 116 which is entrained around a sprocket 118 fixed on the main drive shaft 56. The other end of the chain is connected to one end of an extension spring 120 and the spring is secured at its other end to a pin 122 provided in a web 124 extending between the sidewalls 89 and 22. Thus, as the platen roller P is driven in a forward stroke in spaced relation above the printing station, the driver lever 8 pulls the drive cable 112 forwardly (from left to right as viewed in these FIGS.) thereby rotating the main drive shaft in an anticlockwise direction against the action of the spring 120. On the rearward stroke of the drive lever 8, the platen is lowered into printing engagement with a form at the printing station and the main drive shaft is rotated in the opposite direction under the influence of the spring 120 which maintains the drive cable 112 in a taut condition. Accordingly, the feeder derives its motion directly from the motion of the platen mechanism.

The proportions of the above described cable drive are so chosen that the motion of the arm 8 is converted to approximately 330° of rotary motion of the main drive shaft 56 in either direction.

On the forward stroke of the platen the resulting rotation of the main drive shaft is used to drive the pullout rollers 62 and 64 and the conveyor tape 90 about 11 inches. This motion is sufficient to ensure that all forms reach the printing station with motion to spare.

Drive to the conveyor tape 90 and the pullout rollers 62 and 64 is taken from the main drive shaft 56 by means of a one-way clutch 130 associated with conveyor tape sprocket 100. Thus, on the rearward stroke of the platen, while a form is being imprinted, no drive is imparted to the conveyor tape or the pullout rollers.

Drive for the separator rollers 28 is also taken from the main drive shaft 56 by means of a one-way clutch 132 associated with the separator roller sprocket 52; however, this clutch is oriented to drive on the rearward stroke of the platen. Therefore, forms are fed to the printing station by the pullout rollers and the conveyor tape during the forward stroke of the platen, and are advanced to the preprint station by the separator rollers during the rearward stroke of the platen.

One-way clutches (not shown in the drawings) are also provided in each of the pullout rollers 62 and 64, to permit the rollers to overrun when a form is being advanced to the preprint station by the separator rollers 28. Also, the one-way clutch 132 of the separator rollers permits the separator rollers to overrun as a form is being withdrawn from the stack by the pullout rollers 62 and 64.

A form stop device indicated generally at 140 is provided to accurately position a form at the printing station. As shown in FIGS. 3 and 5, the form stop device includes a stop member 142 adapted to be raised and lowered in timed relation with the printing cycle of the machine and, also, adapted to be moved in fore and aft directions to accommodate varying size forms or varying the location of an impression on the form.

The raising and lowering of the stop 142 is under control of a cam 144 provided on the main drive shaft 56. A cam follower 146 is pivotally mounted on a pin 148 provided in the sidewall 22, and extends from the cam to an actuator 150. The actuator is pivotally mounted on a pin 152 projecting from a web 151, and is provided with an elongate lip 154 projecting downwardly towards the printing station. A connecting element 156 is pivotally mounted on a pin 153 and includes an

ear 158 at one end adapted to ride on the lower edge of the lip 154, and at its other end it is secured to and carries the form stop 142. Thus, when the main drive shaft is driven in the direction to advance a form from the preprint station to the printing station, (counterclockwise as viewed in FIG. 4) a depression in the cam surface is presented to the follower so that the actuator is effective to allow the element 156 to swing about the pivot 153, as a result of the lip 154 retreating from the ear 158 of the element 156. This movement causes lowering of the stop 142 into the path of a form carried by the tape to position and hold the form at the printing station. On completion of the imprinting of the form, the main drive shaft is rotated in the opposite direction and the stop is restored to its raised position.

The fore and aft movement of the stop is manually controlled by means of a rack 160 provided with apertures 162, a pinion 164 meshing with the apertures, and a manually operated rod 166 rotatably supported in the sidewall 22 and web support 168. As best shown in FIG. 5, the rack 160 includes a back plate 170 having a pair of elongate slots 171 and 173 therein, and a top plate containing the apertures 162 formed at right angles to the back plate. The rack is slidably mounted on a pair of pins 174 and 176 provided in the sidewall 89, such that the pins pass through the slots 171 and 173 permitting fore and aft movement of the rack within the limits of the slots.

The pinion 164 is fixed to one end of the rod 166 and in engagement with the apertures 162. A knob 178 is provided at the other end of the rod such that by turning the knob the shaft and the pinion are rotated to thereby move the rack 160. However, the rack is also associated with the element 156 by means of a formed ear 180 which also supports the pivot pin 153 fixed in the back plate 170. Thus, as the rack 160 is moved through rotation of the rod 166, its interconnection with the element 156 also imparts forward or backward movement to the stop 142 carried thereby. The ear 158 continues to ride on the lower edge of the elongate lip 154 of the actuator 150 so that regardless of the position of the stop 142, the lip will be effective to act against the ear 158 when the actuator 150 is pivoted by the follower 146 and the cam 144. Preferably, the actuator is also provided with a screw 182 and a lock nut 184 to adjust the location of the zone of movement imparted to the actuator and, of course, to the form stop 142.

A detection means is provided and comprises a sensing finger 190 pivotally mounted on a bracket 191 which is fastened to the underside of the deck plate 24. As shown in FIG. 4, the sensing finger has an end adapted to coact with a form detector switch S3, and an end 192 which projects upwardly through an opening in the deck plate to sense for the presence or absence of a form at the preprint station.

At this point it should be explained that, since a printing plate is fed to the printing station PS each cycle of the machine, it is necessary that a form to be imprinted also be advanced to the printing station, i.e., if a form misfeeds and does not reach the printing station, the platen P will go through a printing stroke without the form and the printing plate will be advanced to the receiving drawer. This, of course, would result in the loss of an impression from that plate and would require that the plate subsequently be returned to the feed magazine and again advanced through the printing station.

The detection means avoids loss of a plate at the printing station and is designed to shut down the machine in the event of a form feed failure. The machine is shut down if the sensing finger 190 does not sense the presence of a form at the preprint station when it is supposed to be there, and it is also shutdown if the sensing finger does not sense the departure of the form from the preprint station at the appropriate time.

With reference to FIGS. 3 and 6, the detection means includes in addition to the sensing finger 190 and the form detector switch S3, a pair of timing switches S1 and S2, under control of cams C1 and C2 respectively, mounted on the main drive shaft 56, and a forward and reverse switch FRS controlled by a cam C3 on the main drive shaft.

The cam C3 is frictionally driven by the main drive shaft 56 and controlled by a pin 193 so that it swings promptly to one position or the other to place the switch FRS on a contact representing the direction of rotation of the shaft 56. In FIG. 6 the upper contact is the anticlockwise contact or forward platen stroke contact, and the lower contact is the clockwise contact or rearward platen stroke contact (printing stroke contact).

FIG. 6 is in part a diagrammatic view of the cam carrying portion of the main drive shaft 56, and shows the same as viewed in the FIG. 4 direction, or as looking from the left in FIG. 3. FIG. 6 is intended to illustrate the parts in approximately the positions which they occupy when a rearward or printing stroke of the platen P has just been completed and a forward or nonprinting stroke is about to begin. This is equivalent to the condition at the commencement of the counterclockwise motion of the main drive shaft 56. This direction of rotation of the main drive shaft drives the conveyor tape 90 and the pullout rollers 62 and 64, during the forward stroke of the platen P, and advances the form from the preprint station to the printing station, and the form at the printing station to the receiving hopper.

As the platen starts to move forward, the cam C3 will shift the switch FRS to the upper contact and hold it there, and the form F will normally be advanced from the position shown to the printing station, ultimately releasing the sensing finger 190 so that the switch S3 drops to the lower contact. When the switch S2 is closed by the cam C2 slightly later during the cycle, to interrogate switch S3, no circuit will be completed and the printing machine will continue to operate. If, however, the form F failed to leave the preprint station, the interrogation by the switch S2 would complete a circuit through switches S3, S2 and FRS to shut the printing machine down. It will be understood, of course, that suitable conventional electrical connections (not shown) are provided on the printing machine for disabling it when the circuit of FIG. 6 is completed.

After the platen completes the forward stroke and starts its rearward or printing stroke, the main drive shaft 56 will start to rotate in a clockwise direction. This rotation of the main drive shaft drives the separator rollers 28, during the printing stroke of the platen, to separate a form from the front of the stack and advance it to the preprint station. This rotation of the shaft also causes the cam C3 to shift the switch FRS to the lower contact. As a form F is fed out of the hopper to the preprint station 14, it will, of course, actuate the sensing finger 190 and shift the switch S3 to its upper contact. At an appropriate subsequent time during the cycle the cam C1 will close the switch S1 to interrogate the switch S3. In their described positions no circuit will be completed and the printing machine will continue to operate. If, however, the form F failed to arrive at the preprint station when due the interrogation by the switch S1 would complete a circuit through S3, S1 and FRS to shut the printing machine down.

In summary, the switch S3 indicates the presence or absence of a form at the preprint station, the switch S2, through the switch FRS, checks the switch S3 for the departure of a form from the preprint station on the forward or nonprinting stroke of the platen, and the switch S1 through the switch FRS checks the switch S3 for the arrival of a form at the preprint station during the rearward or printing stroke of the platen.

Thus, on the forward stroke of the platen only the conveyor tape 90 and the pullout rollers 62 and 64 are driven, and on the rearward stroke of the platen only the separator rollers 28 are driven.

In the event a form is not properly separated from the stack and, therefore, does not reach the preprint station, thus causing shutdown of the machine, all that is necessary to restore the machine to operative condition is to free the hopper jam, if any, and then rotate the shaft 48 with the knob 58 in a clockwise direction as viewed in FIG. 4, to thereby advance the form to the preprint station. At this time the machine can be turned on and the printing plate at the printing station is not lost by being fed to the receiving drawer.

Similarly, if a form fails to depart the preprint station as intended causing the machine to shut down, the operator merely corrects whatever condition caused the malfunction, and manually advances a form to the print position. The form is, of course, removed from the sensing finger 190 and the machine can be turned on and its operation continued.

The feeder of the present invention is also provided with a self-regulating means for automatically timing the actuation of the interrogation switches S1 and S2 and the form stop operation in proper relation with the printing machine stroke when the feeder is initially installed on a machine. This is found to be desirable since there is sufficient variance in machine dimensions that there is a noticeable discrepancy in the location of the feeder hopper in relation to the printing station and cable attachment point on various machine. With reference to FIGS. 3 and 6, the means for accomplishing this comprises a timing disc 202 which is drivingly associated with cams S1, S2 and 144, all of which, as a group, are connected to the main drive shaft 56 through a slip clutch 200. The timing disc is provided with a projection 204 adapted to coat with a stop pin 206 provided in the side plate 22.

Thus, when the feeding device is placed in position on the machine, a form is manually advanced to the preprint station by rotating the shaft 48 with the knob 58. When the machine is turned on, the main drive shaft is driven to advance the form to the printing station. As the main drive shaft is rotated, the timing disc is also rotated until the projection 204 thereon abuts the stop pin 206. If the timing is not precisely correct, the slip clutch 200 is effective to permit the main drive shaft to continue to rotate through the balance of a complete machine cycle while the timing disc and its associated cams are held against rotation by the pin 206. This operation requires only one machine cycle to position the parts in proper timed relation with the printing stroke of the machine, and once the timing disc is set it continues to maintain a proper timing relation of the cams until the feeder is shifted to another printing machine.

When the feeder device is removed from the printing machine it is merely necessary to unplug an electrical control connection to the main printing machine, loosen the clamping means 4, and then to disconnect the drive cable 112 from the drive lever 8. When the drive cable is disconnected its free end, which is provided with a hook 210, is secured to a storage pin 212 provided in the sidewall 89, see FIG. 3.

However, when the feeder device is again mounted on the machine, it would be somewhat difficult to grasp the free end of the cable to pull the same against the action of the rather strong spring 120 in order to connect the cable to the drive lever 8. Therefore, means have been provided for mechanically pulling the cable comprising an arm 214. As shown in FIG. 3, the arm is pivotally mounted at 216 on a plate 218, and the plate is fastened to the web 124 and a similar web 220. One end of the arm is provided with a pair of projections 222 between which the cable passes, and the cable is provided with a stop enlargement 224 fixed thereon to prevent the free end of the cable from passing between the projections and around the pulley 114.

In operation, the arm 214 is moved in an anticlockwise direction as viewed in FIG. 3, thereby causing the projections 222 to act against the stop 224 and withdraw a sufficient length of the cable from the pulley to connect it to the drive lever. This arrangement affords a mechanical advantage which provides for easy withdrawal of the cable from the pulley against the action of the spring 120.

Summarizing the operation of the feeding device, a form is advanced from the stack to the preprint station 14 by manually rotating the separator rollers 28 with the knob 58. The printing machine is now turned on and the main drive shaft is driven in a direction to cause the pullout rollers 62 and 64 and the conveyor tape 90 to advance the form to the printing station. At this time the platen is being driven in a forward direction and the form stop 142 is lowered, at a time when the trailing edge of a previous form would have cleared the printing station, to stop the unprinted form when it arrives at the

printing station. Since the sensing finger 190 detected the departure of the form from the preprint station, there is no circuit completed and the machine operation is allowed to continue.

- 5 When the forward stroke has been completed, the motion is reversed and the main drive shaft is rotated in the opposite direction, thereby driving the separator rollers to advance the next form to the preprint station, and discontinuing the driving of the pullout rollers and the conveyor tape while the platen is 10 printing on the form at the printing station. Since the sensing finger 190 detected the arrival of the form at the preprint station on time, there is no circuit completed and the machine operation is allowed to continue. During the latter portion of 15 the stroke the form stop is raised so that the printed form will be free to progress to the receiving hopper 18 under the influence of the conveyor tape on the succeeding forward stroke.

On completion of the imprinting operation the pullout rollers and the conveyor tape are again driven to deliver the form at the preprint station to the printing station and the imprinted form to the receiving hopper 18, the form stop lowering at the proper time to detain the incoming unprinted form at the precise printing position.

- 20 25 From the foregoing, it will be seen that the present invention provides a novel feeding device for feeding forms or other sheetlike workpieces in timed relation with a printing or other work machine operation. The feeding device provides for advancing a form to the printing station and a form at the printing 30 station to the receiving hopper during one machine stroke such as the forward stroke of the platen, and to withdraw the next form in the stack and deliver it to a ready or preprint station during a reverse machine stroke such as the stroke of the platen while the form at the printing station is being imprinted. 35 Also, the detection means avoids the loss of a printing plate at the printing station in all instances wherein the conditions of form presence or absence at the preprint station are not satisfied. These combined features result in a feeding device 40 which is compact, reliable in operation and relatively inexpensive to manufacture.

Moreover, there is provided a novel form of transport which is capable of moving a workpiece by one end only with a single tape as effectively and efficiently as do transports which use plural tapes. This makes it possible to provide much greater latitude as to where the impression or work on the form of workpiece may be placed, in addition to providing a much less complex and expensive structure.

Since the drive for the demountable feed mechanism is 45 taken directly from an operating element on the printing or primary work machine it is possible to achieve precise synchronous operation by means of an extremely simple and inexpensive construction.

While the preferred embodiment of the invention has been 50 described and illustrated, it is to be understood that this is capable of variation and modification. Accordingly, the aim in the appended claims is to cover all such variations and modifications as may fall within the true spirit of the invention.

- I claim:
- 55 1. An accessory device for feeding sheetlike workpieces to a cyclically operating work machine having a work station, and a moving portion which is located on the work machine as a permanent part thereof, and is cyclically driven thereby, which comprises:
- 60 65 a frame which is readily attachable to and detachable from the work machine;
- a hopper on the frame for holding a stack of workpieces each having a work area for presentation to the work station for a work operation;
- 70 75 means one the frame for separating a workpiece from the stack and moving it to a ready position;
- 80 transport means on the frame for carrying the workpieces from the ready position past the work station to a discharge point, comprising only one moving tape leading from the ready position past one side of the work station

and arranged to engage each workpiece at one side thereof outside the work area thereof, and a plurality of holdown rollers on the frame urged towards the tape, each so mounted and oriented as to roll only about an axis parallel to the tape surface and substantially normal to the direction of tape movement, and spaced closely enough together so that at least two rollers are in engagement with a workpiece at all times until the workpiece is leaving the tape; and

means readily connectable with and disconnectable from the moving portion for driving the separating means and the transport means from said moving portion in timed relation therewith.

2. An accessory device as set forth in claim 1 in which there is also provided:

a stop member on the frame shiftable into and out of an operative position for arresting a workpiece at the work station; and

means on the frame associated with said readily connectable and disconnectable means, to drive said stop member in timed relation with said work machine.

3. An accessory device as set forth in claim 2 which further includes means to adjust the location of said stop member on said frame so as to occupy different selected positions with respect to said work station without affecting the stop member drive.

4. An accessory device as set forth in claim 3 in which the location adjusting means for the stop member comprises a rack and pinion wherein the rack carries a pivot upon which the stop member is mounted, and the pinion is connected with a manual control knob for operator actuation.

5. An accessory device for feeding sheetlike workpieces to a cyclically operating work machine having a work station and a reciprocating element which is located on the work machine as a permanent part thereof, and is cyclically driven thereby, which comprises:

a frame which is readily attachable to and detachable from the work machine;

a hopper on the frame for holding a stack of workpieces; means on the frame for separating a workpiece from the

stack and moving it to a ready position; transport means on the frame for carrying workpieces from the ready position past the work station to a discharge point; and

mechanism readily connectable with and disconnectable from the reciprocating element for driving the separating means and the transport means from the reciprocating element when connected thereto, said mechanism comprising means for driving the separating means in one direction of movement only of the reciprocating element, and means for driving the transport means in the other direction of movement only of the reciprocating element.

6. An accessory device as set forth in claim 5 which also includes a stop member shiftable on the frame into and out of operative position for arresting a workpiece at the work station, and in which there is means on the frame, associated with the readily connectable and disconnectable means, for driving the stop member to operative position in the same direction of motion of the reciprocating element as that which drives the transport means.

7. An accessory device as set forth in claim 6 which further includes means to adjust the location of said stop member on said frame so as to occupy different selected positions with respect to the work station without affecting the stop member drive.

8. A device as set forth in claim 5 which further includes de-

tection means for stopping the operation of the work machine in case a workpiece is not transported to the work station comprising:

a sensing finger at the ready position for sensing the presence or absence of a workpiece thereat;

a first means operable to stop the work machine in response to the sensing finger detecting the presence of a workpiece at the ready position during the transport operation; and

a second means operable to stop the work machine in response to the sensing finger detecting the absence of a workpiece at the ready position during the operation of the separating means.

9. An accessory device for mounting on and feeding sheet-

like workpieces to printing machines of a predetermined type, said printing machines each having a printing station, and having a moving element acting in time with the printing operation, wherein the nature of the printing machines is such that minor differences can occur in the location of the accessory device relative to the moving element in mounting the accessory device on one or another of the printing machines, said accessory device comprising:

a frame which is readily attachable to and detachable from the work machine;

a hopper on the frame for holding a stack of workpieces; means on the frame for separating a workpiece from the

stack and feeding it to and past the printing station; means on the frame for positively stopping the workpiece at the printing station during printing and thereafter releasing it to be carried beyond the printing station to a discharge point;

means for driving the separating means and the feeding means from the moving element including an element readily connectable to and disconnectable therefrom;

said driving means including a self-regulating means for shifting the timing of the operation of said stopping means to correct for said minor differences in the location of the accessory device with respect to the moving element.

10. A device as set forth in claim 9 in which said self-regulating means comprises a sleeve member normally drivingly but frictionally associated with a shaft on the accessory driven from said moving element, said sleeve member having an abutment surface, and an abutment in fixed relation to the axis of said shaft for encountering the abutment surface on said sleeve to shift the same to properly timed position; and in which the drive means for said stopping means includes a cam operatively associated with said sleeve.

11. A device as set forth in claim 9 in which there is also provided sensing means for determining the location of workpieces at appropriate times during the operation and means for arresting the operation of the printing machine in case a workpiece is not sensed at the appointed time, and timing means for controlling the operation of said sensing and arresting means, said timing means being also associated with and controlled by said self-regulating means.

12. A device as set forth in claim 11 in which said self-regulating means comprises a sleeve member normally drivingly but frictionally associated with a shaft on the accessory driven from said reciprocating member, said sleeve member having an abutment surface, and an abutment in fixed relation to the axis of said shaft for encountering the abutment surface on said sleeve to shift the same to properly timed position; and in which the drive means for said stopping means and the timing means for said sensing and arresting means include cams operatively associated with said sleeve.
